UNITED STATES PATENT OFFICE.

JOSEPH ELGER, OF CHICAGO, ILLINOIS.

LIQUID-COOLING APPARATUS.

1,323,587.

Specification of Letters Patent.

Patented Dec. 2, 1919.

Application filed January 24, 1918. Serial No. 213,547.

To all whom it may concern:

Be it known that I, JOSEPH ELGER, a citizen of the United States, residing at Chicago, in the county of Cook and State of Illinois, have invented new and useful improvements in Liquid-Cooling Apparatus, of which the following is a specification.

This invention relates to apparatus for cooling the water which circulates in the jackets around the cylinders of internal-combustion engines.

The invention has for its object to provide a water cooling apparatus which is very simple in construction and highly efficient in operation, and in which no pump or mechanical device is necessary to produce a circulation through the water jacket of the cylinders. The apparatus is also entirely devoid of thin metal water cooling tubes, and the trouble and annoyance of a clogged cooling system is therefore eliminated. The apparatus also does not require a fan for cooling the water.

The object stated is obtained by means of a novel combination and arrangement of parts to be hereinafter described in detail, and in order that the same may be better understood, reference is had to the accompanying drawing forming part of the specification. The preferred embodiment of the invention has been shown, but it will be understood that various changes and modifications may be made without departure from the spirit and scope of the invention as claimed hereinafter.

In the drawings,

Figure 1 is a vertical section of the apparatus, and

Fig. 2 is a cross section on the line 2—2 of Fig. 1.

Referring specifically to the drawing 5 denotes a casing suitably shaped so that it may be carried at the front end of a motor vehicle, it being understood that the cooling apparatus is designed more particularly for automobile engines. Near the top, the casing is entered by a water inlet pipe 6 and near the bottom a water outlet pipe 7 is connected to the casing. These pipes are suitably connected to the water jacket of the engine cylinders, and as such connections are immaterial to the present invention they have not been illustrated. In the pipe 7

is a check valve 8 to prevent a return flow through said pipe to the casing 5.

In the casing 5 near the top thereof and below the level where the inlet connection 6 is made, is a horizontal partition 9 having a series of perforations 10 so that the water discharged on the partition is broken up into minute particles and trickles down to the bottom of the casing.

Below the partition 9, the interior of the casing 5 is crossed by a series of air tubes 11 the same being open at both ends, and suitably fastened at their ends in opposite walls of the casing, these walls being the front and rear walls, so that when the car is in motion the air is forced through the tubes. The air tubes are thus cooled, and as they are located beneath the partition 9, the water trickles over the tubes and the heat is quickly extracted when the drops of water strike the cool tubes. As the water is divided into fine particles, and it does not flow in a large stream over the cooling tubes, the cooling action is considerably expedited.

On the front end of the casing 5 is an air inlet chamber 12 into which the front ends of the air tubes 11 open. The chamber has an air inlet 13 near the top, and above the tubes 11 the chamber has a vent opening 14 leading from the casing 5 above said tubes. This opening permits the escape of heat from the incoming hot water.

The chamber 12 is provided with a sliding gate 15 for regulating the air intake in cold weather.

When the water in the water jacket of the engine becomes heated it expands and flows through the pipe 6 into the casing 5, and by the way of the pipe 7 it flows back to the bottom of the water jacket. As pointed out hereinbefore, the water trickles down over the air-cooled tubes 11 whereby all its heat is extracted, and it flows back into the water jacket of the engine properly cooled off. The tubes 11 do not extend down to the bottom of the casing 5, so that this portion of the casing forms a water chamber 16. The tubes 11 provide a large heat absorbing area, and the number of tubes employed depends on the amount of cooling surface required to assure the best results.

Where the pipe 6 opens into the casing 5 it is formed with an elongated spreader

nozzle 17 extending in the direction of the length of the casing and serving to spread the water throughout a large area.

I claim:

- 5 A liquid cooling apparatus comprising a casing having a liquid inlet and a liquid outlet, a transverse perforated partition in the casing between said inlet and outlet, and a series of air tubes extending across the

inside of the casing between the partition 1 and the liquid outlet, and opening through opposite walls of the casing, and an air chamber over the inlet ends of the tubes; said chamber having an air inlet and also having a heat vent from the casing on the 15 liquid inlet side of the partition.

In testimony whereof I affix my signature.
JOSEPH ELGER.
